AIR CONDITIONING AND COOLING MACHINE

Julian E. Korts, Baxter Springs, Kans.

Application February 5, 1940, Serial No. 317,442

2 Claims. (Cl. 261—106)

The present invention relates to improvements in air conditioning machines and more particularly to air cleaning, humidifying and cooling machines and an important object of the invention is to provide a compact light weight air conditioning machine having a relatively large capacity.

Another important object of the invention resides in the provision of an improved filter construction.

A further object is to provide improved means to automatically moisten the filter with vaporizable liquid, such as water, so that air passing thru the filter will be cleaned, humidified and cooled.

A still further object is the provision of an air cleaning, humidifying and cooling machine adapted to force large quantities of air thru a moistened filter without tending to generate objectionable spray or mist.

Yet another object of the invention is to provide a machine of the character described and which, for a given capacity, will require less power to operate.

Other objects and advantages of the invention will become apparent during the course of the following detailed description, taken in connection with the accompanying drawings, forming a part of this specification, and in which drawings:

Figure 1 is a view in front elevation of the machine, with a portion thereof broken away and details shown in vertical section.

Figure 2 is a side elevation of the machine.

Figure 3 is a horizontal sectional view substantially on the line 3—3 of Figure 4.

Figure 4 is a vertical sectional view substantially on the line 4—4 of Figure 3.

Figure 5 is a vertical sectional detail view of a float valve preferably forming a part of the invention.

In the drawings, which show only a preferred embodiment of the invention, and wherein similar reference characters denote corresponding parts throughout the several views, the letter A generally designates the improved air conditioning machine, including a housing B for the filter C, filter moisture distributing means D and blower means E, while F designates louvre means carried by the housing B.

In the example shown, the housing B is of substantially semi-cylindrical shape, including a substantially semi-circular base 15, a rectangular front plate 16 provided with a circular opening 17, an arcuately curved rear wall 18 provided

with a rectangular intra-marginal opening 19, and a substantially semi-circular removable cover 20. Secured inwardly adjacent the curved rear wall 18, as by suitable bolts 21, is a rectangular sheet 22 of hardware cloth, such as half inch mesh wire, constituting a protective screen. Formed in opposite sides of the wall 18 are access openings 23, each provided with a closure plate 24, mounted for vertical sliding movement between suitable guide strips 25. Secured in spaced relation to the rear wall 18, as by suitable brackets 26 is a substantially semi-circular iron band 27, forming a hand-rail by which the housing may be readily moved. If desired, suitable diagonal braces 28 may be provided interiorly of the housing.

Of semi-cylindrical shape, the filter C is disposed inwardly adjacent the curved rear wall 18 of the housing B, and comprises an inner ply 30 of wire cloth, such as one inch mesh poultry netting, and a fabric coating 31 of porous absorbent material of one or more layers, the number of layers varying with the kind of material used and also with the exposed surface area thereof as compared with the volume of air to be handled and the type of power unit to be employed. In the example shown, 8 layers of 16 x 20 mesh cheesecloth are provided with an exposed area of 120 square feet. The ply 30 of wire cloth and the coating 31 of porous material are pleated to form a plurality of closely spaced dihedrally disposed panel sections 32, which are self-supporting due to the rigidity of the ply 30 of the wire cloth. I have found that the coating 31 of absorbent material will not actually require any support other than that furnished by its proximity to the ply 30 of pleated wire cloth. However, in assembling the filter, the wire cloth may be painted with enamel, varnish or the like and the first layer of the absorbent material laid thereon. The remaining layers of the absorbent material are then applied over the first layer, either before or after the wire cloth has been pleated. While the absorbent coating 31 may be of a size to permit draping over the top edges of the ply 30 of wire cloth, so as to facilitate uniform distribution of moisture to the material, the coating, as actually manufactured, is of a size to terminate below the upper edge of the wire cloth, and an absorbent wad 33 is interposed between the upper margins of each pair of adjacent dihedral panel sections 32.

Referring now to the filter moisture distributing means D, the same may comprise a lower trough 35, of annular segmental shape,

resting on the base 15 of the housing; and receiving intermediate its end portions 36, 37, the lower end portion of the filter C. Disposed above the filter C is an upper trough 38, of annular segmental shape and including side walls 39 disposed inwardly of the side edges of the filter C and end walls 40 of a height greater than that of the side walls and substantially aligning with the end edges of the filter C. Externally applied to the bottom and sides of this upper trough 38 is a relatively thick porous absorbent coating 41. For satisfactory and lasting performance, this coating 41 should be at least one-eighth of an inch thick, and may comprise from eight to twenty layers of muslin; or from ten to forty layers of cheesecloth; or from eight to twelve layers of burlap; or it may be formed of any other suitable material. The filter coating 41 must be of relatively open mesh to allow the passage of air therethru, whereas the upper 20 trough coating 41 needs only be absorbent. As clearly shown in Figure 4 of the drawings, this coating 41 extends over the side walls 39 and includes marginal portions 42 interiorly adjacent the side walls 39 and terminating above 25 the bottom of the trough 38. Resting on the top of the filter C and contacting each of the absorbent wads 33 thereof may be provided an annular segmental strip 43 of porous absorbent material on which the coated upper trough 38 is 30 disposed. Extending upwardly from the bottom of the lower trough 35 at opposite ends of the filter C are spaced apart uprights 44 provided at their upper ends with screw-threaded studs 45 carrying nuts 46. Projecting laterally from 35 the end walls 40 of the upper trough are lugs 47 resting on the nuts 46 and provided with openings 48 thru which the studs 45 loosely extend. The arrangement is such that, with the intermediate portion of the upper trough 38 resting on the filter C, the trough may be brought to a 40 level position by adjustment of the nuts 46 on the studs 45. As the porous absorbent coating 41 and the strip 43 on which the trough rests are formed of resiliently compressible material, the trough may ordinarily be leveled without affecting the moisture-transmitting capacity of the contact between the coating 41 and the strip 43.

Extending into the housing B is a supply pipe 50, provided exteriorly of the housing with a manually operable valve 51, and interiorly of the housing with a valve 52 operable by a float 53 disposed in the end portion 36 of the lower trough 35. This float valve 52, as shown in Figure 5, includes a stem 54 terminating at its upper end in a conical valve head 55 coacting with a conical valve seat 56. Instead of providing a packing between the stem 54 and the valve body 57, I prefer to encircle the stem with a flexible disc 58 of any suitable material such as rubber, centrally clamped to the stem as by nuts 59, and circumferentially clamped between sections 60, 61 of the valve body 57, as by a coupling sleeve 62. Extending from the float valve 52 is a pipe 63 including a riser portion 64, a horizontal portion 65 above the level of the upper trough 38 and a downturned terminal portion 66 disposed in the upper trough substantially midway its ends.

Mounted in the lower trough 35, at its end portion 37, as shown in Figures 1 and 3, is a water pump 70 and extending therefrom is a pipe 71 discharging at its upper end 72 into the upper trough 38. Connected to the pump 75

70 is an electric motor 73 provided with a suitable cord 74 containing the usual conductors 75 for supplying electrical energy to the motor. Interposed in the cord 74 is a suitable manual control device, such as a switch 76, for starting and stopping the motor 73.

Any suitable type of fan or blower means E for creating a suction zone and a pressure zone, one of said zones being disposed transversely of the concave side of the arcuate filter C, may be employed. In the example shown, spaced coaxial bearings 80 are carried by a platform 81 supported above the base 15 as by legs 82. Rotatably mounted in the bearings 80 is a shaft 83 provided at its forward end with a four bladed screw-type fan 84, aligning with the opening 17 in the front plate 16. Secured to the base 15 beneath the platform 81 is an electric motor 85 provided with a drive pulley 86 connected as by a suitable belt 87 with a driven pulley 88 fixed on the rear end portion of the fan shaft 83. The circumference of the driven pulley 88 may be considerably greater than that of the drive pulley 86 so that sufficient power will be derived from the relatively small motor 85 to properly rotate the fan. If desired, current for the supply cord 14' of the motor 85 may be obtained by tapping the cord 14 at a point 74a in advance of the switch 76.

In order to control the entrance into or exit from the housing of air passing thru the opening 17, any suitable louvre means F may be provided. Secured to the front plate 16 of the housing at opposite sides of the opening 17, as by brackets 90, are spaced apart vertical strips 91, supporting a plurality of spaced horizontally disposed louvres 92, as by stubs or pins 93, for rotary movement about axes longitudinally of the louvres. These louvres 92 may be connected for simultaneous adjustment in any suitable manner. In the example shown, a wire rod 94 is provided having arcuately deformed portions 95 extending thru openings 96 in the louvres. At its upper end, the rod 94 may be turned to provide a dog 97 for releasable engagement with any one of a plurality of openings 98 in the front plate, the rod 94 being sufficiently flexible to permit withdrawal of the dog 97 from any opening, so that the rod may be releasably secured in an elevated or lowered position whereby to permit variation in the angular position of the louvres.

The machine usually is placed in a window opening in a manner to permit access to the closure plates 24 and those parts in back of the front plate 16 from the rear side of the wall. To bring the machine into operation, the water supply valve 51 is opened and the electric cord 14 is connected to a source of current. Assuming the machine to be dry, and the float 53 down, the needle valve 52 will permit the flow of water into the upper trough 38. Upon entry of the supply water into the upper trough, the porous absorbent coating 41 and its marginal portions 42 will become wet thru capillary action or a momentary overflow of the trough side walls 39. Thus primed, the wet coating 41 will siphon the supply of moisture over the trough side walls 39 and downwardly into the annular segmental strip 43. The rate of flow through the needle valve 52 is less than the moisture carrying capacity of the upper trough coating 41 so that water supplied to the upper trough will not tend to overflow except thru the coating 41. The moisture in the segmental strip 43 will tend to

seep in an unevenly distributed manner into the absorbent wads 33 and from the latter thru the absorbent coating 31 of the filter C and into the lower trough 35. When the lower trough is filled to a predetermined level, the float 53 will of course, act to shut off the supply of water to the upper trough thru the valve 52. Depending on the direction of rotation of the fan, there will be either a pressure or suction of air thru the filter C, so that evaporation of the moisture in the absorbent coating 31 will occur simultaneously with a cooling and humidifying of the current of air. Should the absorbent coating 31 tend to dry out near its lower margin due to depletion of the supply of water in the upper trough, a quantity of water sufficient to maintain the coating in a moist condition will be absorbed from the lower trough thru capillary action of the coating, whereby to lower the water level in the lower trough. Thereupon, the valve 52 will open and bring about a resumption of the supply of water to the upper trough. After the machine has operated for a certain length of time, the water level in the lower trough will tend to become stabilized at a height to maintain the float valve in a substantially constant partially closed position whereby to reduce the flow of water into the upper trough 38 to the exact amount being removed from the filter C thru evaporation. An increase in the moisture content of the incoming air to be conditioned will of course decrease the evaporation of moisture from the filter C, thus resulting in a surplus of moisture reaching the lower trough, but this surplus will of course elevate the float and thereby decrease the supply of water to the filter C.

Since internal obstructions to the uniform flow of air thru the filter due to the design of the machine may tend to result in uneven evaporation of moisture from the filter C and the appearance of dry spots therein, the thickness of the porous absorbent coating 31 of the filter C may be increased at those portions of the filter where there is a greater flow of air, or the upper trough coating 41 may be made thicker above those portions of the filter coating 31 tending to dry out so as to conduct a greater supply of moisture thereto. Upon resumption of operation of the machine A following a lapse in its use, substantially all the water in the machine may be contained in the lower trough, thus tending to maintain the float valve in its closed position. However, the lower portion of the filter C will still be in a moist condition by reason of its capillarity and after a few minutes of machine operation, will have removed sufficient water from the lower trough to cause valve 52 to open and

bring about a resumption of the water supply to the upper trough. By manipulation of the control switch 76, the circulating pump 70 may be placed in operation.

5 It will be understood that the circulating pump may be continuously operated in conjunction with the remainder of the machine to supply the upper trough with a quantity of water greater than the amount actually consumed thru evaporation from the filter C. Any water not vaporized from the filter C will of course drain into the lower trough and thereby become available for recirculation. If desired, the marginal portions 42 of the absorbent coating 41 of the upper trough may obviously be omitted and under this condition, moistening of the filter C will necessarily depend on the flow of water over the side walls 39 of the trough.

10 It will therefore be seen that I have provided an improved machine for cleaning, cooling and humidifying air and wherein an improved semi-cylindrical filter member is provided in conjunction with a blower fan adjacent the concave side thereof.

15 20 Various changes may be made in the form of invention herein shown and described without departing from the spirit of the invention or the scope of the following claims.

I claim:

25 30 1. An air conditioning device comprising elevated distributing means for a vaporizable liquid such as water, a lower container, an arcuate porous member for conducting the liquid from said means to the lower container, said member being formed of fabric pleated to provide substantially vertically disposed dihedral panel sections, means to supply said liquid to said distributing means, and means creating an air suction zone and an air delivery zone, one of said zones being disposed transversely of the concave side of the arcuate porous member to produce a substantially uniform draft of air thru said member.

35 40 2. An air conditioning device comprising an arcuate porous member formed of pleated fabric to provide a plurality of substantially vertically disposed reentrant dihedral panel sections, means to substantially uniformly moisten the porous member with a vaporizable liquid, such as water, said means including an annular segmental porous strip superjacent said porous member, an annular segmental trough adapted to distribute said liquid thruout the length of said strip and means to supply said liquid to said trough, and means disposed transversely of the concave side

45 50 55 of the arcuate member to produce a substantially uniformly distributed draft of air thru said porous member.

JULIAN E. KORTS.
